United States Patent Office.

JOHN F. RIGGS AND WILLIAM M. ALBIN, OF SAINT JOSEPH, MISSOURI

Letters Patent No. 67,453, dated August 6, 1867.

IMPROVED WASHING MACHINE.

The Schedule referred to in these Letters Patent and making part of the same.

TO ALL WHOM IT MAY CONCERN:

Be it known that we, JOHN F. RIGGS and WILLIAM M. ALBIN, of Saint Joseph, in the county of Buchanan, and State of Missouri, have invented a new and improved Clothes-Washing Machine; and that the following description, taken in connection with the accompanying drawings, hereinafter referred to, forms a full and exact specification of the same, wherein we have set forth the nature and principles of our said improvements by which our invention may be distinguished from all others of a similar class, together with such parts as we claim, and desire to have secured to us by Letters Patent.

This invention relates to a new and improved clothes-washing machine of that class which is provided with a reciprocating plunger to compress the clothes in the suds-box, and by its action turn the clothes therein while compressing them, so that they will all be acted upon alike, and all thoroughly cleansed.

The invention consists in the novel means employed for operating the plunger, and in the arrangement of certain detail parts, as hereinafter fully shown and described, whereby a very efficient clothes-washing machine is obtained. In the accompanying sheet of drawings—

Figure 1 is a longitudinal central section of our invention.

Figure 2, a side view of the same.

Figure 3, a detached view of the lower part of one of the legs of the same.

Similar letters of reference indicate like parts.

A represents the suds-box of the machine, which stands on four legs, *a a' a'*, the former, *a*, which are at one end of the machine, being each composed of two parts, connected by a hinge, *b*, the hinges being applied in such a manner as to admit of the lower parts of the legs being turned outward when desired, and the two parts being kept rigid, when necessary, by a slide-latch, *c*, shown more particularly in fig. 3. B is a wheel, the shaft *d* of which has its bearings in the upper parts of the legs *a*. This shaft *d* has a crank, *e*, upon it, from which motion is given an oscillating frame, C, by means of a connecting-rod, D, the outer part of the latter being round, and passing loosely through a rod, *f*, in the lower part of the frame C, the ends of the rods having round journals, which are allowed to turn in the side pieces of the frame, the rod D having a pin, *g*, passing through it, at the outer side of the rod *f*, and a spiral spring, E', fitted on the round part of D, between the rod *f* and a shoulder, *h*, thereon. (See figs. 1 and 2.) Within the suds-box A there is an inclined plunger, E, having two arms F attached, which pass through the upper part of one end of the suds-box, and have a series of notches, *i*, made in their under sides to catch over a rod, *j*, in frame C. The end *k* of the suds-box opposite to or facing the inclined plunger E is inclined, and rounded at its lower part, as shown clearly in fig. 1, and to the sides of the suds-box near the end *k* there are fitted handles F', so applied that they may be readily removed when necessary.

The suds-box is supplied with a requisite quantity of suds, the lower parts of the legs *a* turned down or adjusted in a vertical position and secured by the latches *c*, and power applied to the shaft *d*, the wheel B serving as a balance-wheel. A reciprocating motion is imparted to the plunger E from the shaft *d* through the medium of the crank, connecting-rod, and oscillating frame, and the clothes are subjected to the necessary pressure and motion within the suds-box to thoroughly cleanse them, the clothes being turned over as well as squeezed and compressed by the action of the inclined plunger in connection with the inclined end *k*. The plunger E may be made to work nearer to or further from the inclined end *k* of the suds-box by adjusting different notches *i* on the rod *j* in frame C. In moving the device from place to place the lower parts of the legs *a* are turned upward, which allows the wheel B to rest upon the ground, as shown in fig. 2, and the handles F' being applied, the device may be shoved along like a wheel-barrow. When the machine is in use the handles F' are removed so as to be out of the way.

Having thus described our invention, we claim as new, and desire to secure by Letters Patent—

1. Operating the plunger E through the medium of the pivoted frame C, connecting-rod D, and crank *e* of the shaft *d*, substantially in the manner as and for the purpose set forth.
2. The wheel B, in combination with the legs *a a'*, formed of two parts, connected by a joint or hinge, *b*, substantially as and for the purpose specified.

JNO. F. RIGGS,
WM. M. ALBIN.
